TEMPERATURE CONTROLLING DEVICE

Filed Sept. 28, 1944

UNITED STATES PATENT OFFICE

2,454,682

TEMPERATURE CONTROLLING DEVICE

Victor Weber, Greensburg, Pa., assignor to Robertshaw-Fulton Controls Company, a corporation of Delaware

Application September 28, 1944, Serial No. 556,209

9 Claims. (Cl. 236—99)

1

This invention relates to temperature controlling apparatus and, more particularly, to combined snap-acting and throttling thermostatic control devices for controlling the flow of fuel to burners.

It is advantageous in the use of cooking ranges and other heating devices to bring the oven quickly up to a desired temperature and then maintain this temperature for as long a period as desired. In the initial or preheating stage two burners may be employed to obtain a large capacity fuel flow until the set temperature is reached. Thereafter, one burner is automatically shut off and an even temperature is maintained by operation of a single burner under thermostatic control for the duration of the cooking operation.

An object of this invention is to permit heating of the oven selectively with one or more burners, as desired.

Another object of the invention is to automatically shut off all but one burner from further operation when a set oven temperature is reached.

Another object of the invention is to effect the shut-off with snap action while retaining throttling control on the existing burners.

Other objects and advantages will become apparent from the following description taken in connection with the accompanying drawings, wherein:

Fig. 1 is a side elevation, partly in longitudinal section, of the improved temperature control apparatus;

Fig. 2 is a cross-section taken on the line 2—2 of Fig. 1;

Fig. 3 is a cross-section taken on the line 3—3 of Fig. 1; and

Fig. 4 is a fragmentary view similar to Fig. 1 of a modified form.

Referring more particularly to the drawing, a casing 10 is provided with an internal T-shaped partition wall separating the casing into an inlet chamber 14 for fuel and a pair of outlet chambers 16 and 18. The inlet chamber 14 has an open end provided with a closure plate 20 having a fuel inlet connection 22 controlled by a rotatable shut-off cock 24 arranged for manual operation by means of the dial 26. The shut-off cock 24 is provided with an axial bore 28 and a port 30 which affords communication between the connection 22 and the bore 28 in order that fuel may be admitted to the chamber 14 when the port 30 is aligned with the connection 22 upon manipulation of the dial 26.

Passage of fuel between the inlet chamber 14

2

and the outlet chamber 16 is controlled by a thermostatic valve 32 which is reciprocably mounted in the chamber 16. The valve 32 is movable into and out of engagement with a seat formed on the outlet side of an opening 34 in the partition 12 affording communication between the inlet chamber 14 and the outlet chamber 16. The thermostatic valve 32 is mounted upon a stem 36 which projects through the opening 34 and thus has one portion within the chamber 14 and the other portion within the chamber 16. That portion of the stem 36 which extends within the chamber 16 is threaded for engagement with a wing nut 38 which is reciprocable with the stem 36 but held against rotation by engagement with a slotted collar 40 secured in the chamber 16.

The thermostatic element for operating the valve 32 with gradual action consists, in this embodiment, of the usual bulb 42, capillary tube 44 and an expansible element 46 mounted on an end cap 48 which forms a closure for the open end of the outlet chamber 16. The movement of the expansible element 46 may be communicated to the nut 38 through a compensating device, comprising, in this instance, a bimetallic element 50 carried by a housing 51 which is mounted on a connector 52 carried by the nut 38. A spring 54 extends between the nut 38 and the housing 51 and permits the latter to reciprocate on the connector 52 for a purpose apparent hereinafter.

The thermostatic valve 32 is adjustable relative to its seat by the manipulation of the dial 26 to set the temperature at which the control will operate. Such adjustment is effected by a rod 56 which projects axially through the shut-off cock 24 to the chamber 14 and carries an offset tongue 58 overlying the end of the valve stem 36. The rod 56 and the valve stem 36 are in axial alignment and the offset tongue 58 serves to impart rotation of the rod 56 to the stem 36 by the provision of a disc 60 carried on the end of the valve stem 36 and having a slot therein through which the overlying end of the tongue 58 projects.

Communication between the inlet chamber 14 and the outlet chamber 16 is controlled by an auxiliary valve 62 which is reciprocable into and out of engagement with a seat formed on the inlet side of an opening 64 in partition 12. The auxiliary valve 62 is mounted on a valve stem 66 projecting from the closure plate 20 into the chamber 14 substantially parallel with the rod 56 and valve stem 36. The valve 62 is adapted

to be opened manually and closed automatically with a snap action. To this end, there is illustrated in Fig. 1 a plunger 68 carrying a push-button 70 mounted for reciprocable movement within a support 72 carried by the closure plate 20 on one side of the valve stem 36 and extending exterior of the chamber 14. The plunger 68 and push-button 70 are biased outwardly from the support 72 by a coil spring 74 extending between the push-button 70 and a collar formed on the support 72. An enlargement 76 formed on the end of the plunger 68 within chamber 14 and engageable with the plate 20 serves to limit outward movement of the plunger under the bias of the spring 74.

Secured to the inner end of the plunger 68 is an angular plate 78 which extends into the valve chamber 14 intermediate the valves 32 and 62 and is suitably apertured to permit the stem 36 to extend freely therethrough. The movement of the plate 78 in response to operation of the push-button 70 is transmitted to the valve 62 through a pivoted lever 80 having oppositely disposed legs thereon. One of these legs extends into engagement with plate 78 and the other into engagement with a head 82 connected by a neck portion 84 with the valve 62. Preferably, the leg of the pivoted lever 80 which engages the head of the valve 62 is in the form of a yoke which extends around the neck 84 as more fully shown in Fig. 2 of the drawing. The means for biasing the valve 62 to its seat and effecting its closure with snap-action consists of a coil spring 86 carried on the valve stem 36 and extending between the head 82 and the plate 78 for this purpose.

The lever 80 is mounted for the pivotal movement described on a support 88 which is secured in the chamber 14 by means of the screws 90 which serve to attach it to the partition 12. The support 88 carries an integral bearing portion 92 through which the valve stem 36 projects and is thus provided with support for its reciprocable and rotatable movement. A coil spring 93 which is weaker than the spring 86 is carried by the bearing 92 and extends between the valve member 32 and the support 88 to bias the valve member from its seat. The support 88 also carries latching means for maintaining the auxiliary valve open. These comprise a second pivoted lever 94 which is biased in one direction by a tension spring 96 extending between one leg of the lever 94 and the support 88. The spring 96 thus serves to bias this leg of the lever into engagement with the disc 60 carried by the valve stem 36. Preferably, the lever leg is suitably curved in order that close engagement may be maintained with the disc throughout the movements of the valve stem 36. The opposite leg of the lever carries a catch 98 which is adapted to be moved by pivotal movement of the lever 94 into latching engagement with lever 80 when the parts are suitably positioned by operation of the dial 26 and the push-button 70. As will be apparent hereinafter, the disc 60 forms releasing means for the latching mechanism.

As previously indicated herein, the outlet chambers 16 and 18 may communicate with separate burners both located in a single oven. The push-button 70 and dial 26 are adapted to project exteriorly of a front panel 100 of a conventional gas range for convenient operation by the user. The bulb 42 of the thermostatic element may be located within the oven of the range to respond through the expansible ele-

ment 46 to the temperature prevailing therein.

In the operation of the device rotation of the dial 26 will cause the stem 36 to rotate and, due to the threaded connection with the nut 38 and the bias of spring 93, the valve 32 will be moved off its seat. This operation will also cause the shut-off cock 24 to be positioned with the port 30 in registry with the connection 22 so that fuel is admitted to the chamber 14 and the operating temperature is set.

The opening of the valve 32 permits fuel to flow to the outlet chamber 16 and thus to the burner with which it is connected. The disc 60 on the valve stem 36 has been moved axially with the valve 32 but engagement is maintained with the lever 94 due to the tension spring 86 serving to rotate the lever around its pivot. The push-button 70 may now be operated to overcome the bias of the spring 74 and pivot the lever 80 clockwise by means of the plate 78. The catch 98 on lever 94 has been moved into the path of the lever 80 and the tension spring 96 will yield to permit lever 80 to move to the opposite side of the catch 98 from that shown in Fig. 1 of the drawing. Thus, the lever 94 is latched in position by the lever 80. If the dial 26 has been rotated a sufficient amount the engagement between lever 94 and the disc 60 may no longer exist. It will be apparent, however, that such engagement is not essential in carrying out the purposes of this invention.

The opening of the valve 62 by operation of the push-button 70 occurs against the bias of the spring 86 as is apparent. This permits fuel to flow from the chamber 14 to the outlet chamber 18 and thus to the burner connected therewith. With both burners operating, the oven chamber quickly reaches the set temperature of the dial 26 and the thermostatic control 46 thereupon moves the valve 32, through the interposition of the connections described and by compressing the spring 93, to closed position relative to the opening 34 and fuel supply to the outlet chamber 16 is shut off. As the spring 86 is stronger than the spring 93 it is not compressed at this time. This axial movement of the valve 32, and consequently of the valve stem 36, causes the disc 60 to overcome the pull of the tension spring 96 and to pivot lever 94 counter-clockwise to release the latch. Immediately, the spring 86 which biases valve 62 to its seat comes into operation to pivot the lever 80 counter-clockwise and cause the valve 62 to close with snap action. Fuel supply to the outlet chamber 18 is thereupon shut-off and neither burner can operate.

When the oven temperature for which the dial 26 has been set becomes lowered, the valve 32 is opened by operation of the spring 93 to permit sufficient fuel to flow through the opening 34 into the outlet chamber 16 to maintain the desired temperature. Thus, while the valve 32 operates automatically in either opening or closing direction, the valve 62 operates automatically only in the closing direction.

In the event that overshoot occurs during use of the control, the spring 86 will be compressed by the movement of the housing 51 and no damage to the seated valve member 32 will occur.

In the modified form shown in Fig. 4 the separate operation of the push-button 70 and the dial 26 has been dispensed with. The modi-

fication may be simply and economically carried out by substituting a few parts in the embodiment shown in Fig. 1 and, accordingly, similar reference numerals are used in the following description for corresponding parts.

The dial 26 is shown in Fig. 4 as carried on a tubular projection 102 which slides in the bearing formed by the inner wall of a bonnet 104 for the shut-off cock 24 which is carried by the closeure plate 20. As fully described and claimed in Weber Patent No. 2,303,011 the dial and tubular projection may be moved axially toward the plate 20 and also be rotated. In order that the rotative movement of the dial may be imparted to the cock 24, the stem portion 106 thereof carries at its terminal end a slotted collar 108 with which a suitably tongued sleeve 110 cooperates. The sleeve 110 is interposed between the collar 108 and the tubular projection 102 and has a flange 112 on its inner end engaging the wall of an annular recess 114 in the bonnet 104 and being straddled by a slotted portion 116 formed in the adjacent end of the sleeve. A coil spring 118 extends between a shoulder 120, formed on the stem portion 106, and a plurality of inverted projections 122 formed on the sleeve 110 for this purpose.

The plate 20 has a channel-shaped support 124 secured thereto and in which a pin 126 is slidably mounted. The pin 126 engages at one end with the dial 26 and is axially movable when similar movement is imparted to the dial as described. The support 124 has a lug 128 upon which a bell-crank lever 130 is pivoted. One leg of the lever 130 extends into engagement with a plunger 132 projecting from the plate 20. As the plunger 132 and associated parts are identical for all operating purposes with those described in connection with Fig. 1, further description at this point is unnecessary.

In the operation of the modified form shown in Fig. 4, the axial movement of the dial 26 by manual pressure applied thereto against the bias of the spring 118, will cause the pin 126 to actuate the lever 130 and impart axial movement to the plunger 132. As in the previous embodiment, the angular plate 78 is thereupon moved and will perform its described function. The rotative movement of the shut-off cock 24 may be performed, as in the aforesaid patented structure, by rotating the dial while it is held in and the flange 112 moved away from the recess 114. As all the remaining features of the operation and construction of the alternative form may be identical with those described in connection with Fig. 1, further reference may be had to the previous disclosure herein if desired.

It will be apparent that a combination of gradual acting and snap-acting valves has been provided in this embodiment of the invention to control the flow of fuel to fuel burner. The snap-acting valve may be adapted to close at any time, either ahead of or after the gradual acting valve, but in this embodiment the former expedient is preferred. Also, while the thermostatic valve has been described and shown in connection with a shut-off cock, it will be apparent that other means of admitting fuel to the inlet chamber could be provided. In the preferred form, the manual operation of the snap-acting valve is performed separately from the operation of opening the shut-off cock and setting the temperature but it will be understood that these operations could be combined if desired. All these and other modifications could be made

without departure from the spirit of the invention which generally consists of an arrangement capable of carrying out the objects of the invention set forth and in the combination defined in the appended claims.

I claim:

1. A temperature control apparatus for dual burners comprising a casing having a fuel chamber with separate outlets for the burners, a valve movable between open and closed positions relative to one of said outlets, a thermostatic operator for said valve, an auxiliary valve movable between open and closed positions relative to the other said outlet and being biased toward closed position, manually operable means for opening said auxiliary valve, latching means operatively associated with said manually operable means for maintaining said auxiliary valve open, and means carried by said thermostatic valve for releasing said latching means and causing said auxiliary valve to close under said bias upon movement of said thermostatic valve toward closed position.

2. A temperature control apparatus for dual burners comprising a casing having a fuel chamber with separate outlets for the burners, a valve movable between open and closed positions relative to one of said outlets, a thermostatic operator for said valve, an auxiliary valve movable between open and closed positions relative to the other said outlet and being biased toward closed position, manually operable means for opening said auxiliary valve including a pivoted lever, latching means for maintaining said auxiliary valve open including a second pivoted lever engageable with said other lever and adapted to overcome the bias of said auxiliary valve, and means carried by said thermostatic valve for disengaging said levers to release said latching means and cause said auxiliary valve to close under said bias upon movement of said thermostatic valve toward closed position.

3. A temperature control apparatus for dual burners comprising a casing having a fuel chamber with separate outlets for the burners, a valve movable with gradual action between open and closed positions relative to one of said outlets, a thermostatic operator for said valve, an auxiliary valve movable between open and closed positions relative to the other said outlet, means for biasing said auxiliary valve toward closed position, manually operable means for opening said auxiliary valve including a pivoted lever, latching means for maintaining said auxiliary valve open including a second pivoted lever engageable with the other said lever and adapted to overcome said biasing means, and means engageable with said second lever for tripping said latching means upon movement of said thermostatic valve toward closed position and causing said auxiliary valve to close with snap action.

4. A control apparatus comprising a casing having an inlet chamber and a pair of outlet chambers, a partition separating said chambers and provided with separate openings from said inlet chamber to each of said outlet chambers, a valve positioned in one of said outlet chambers and movable to control the opening thereof, means for operating said valve with gradual action, a second valve positioned in said inlet chamber and movable to control the other one of said openings, means for biasing said second valve in one direction relative to the opening controlled thereby, manually operable means for moving said second valve against its bias, means for

latching said second valve in moved position, and means carried by the first said valve for tripping said latching means upon movement of said first valve and causing said second valve to move with snap action.

5. A temperature control apparatus comprising a casing having an inlet chamber and a pair of outlet chambers, a partition separating said chambers and provided with separate openings from said inlet chamber to each of said outlet chambers, a valve movable between open and closed positions relative to one of said openings, a thermostatic operator for said valve, an auxiliary valve likewise movable relative to the other said opening, a single adjusting means carried by said casing and adapted for both rotary and axial movement relative thereto, means for opening said thermostatic valve upon one said movement of said adjusting means, and means for opening said auxiliary valve upon the other said movement of said adjusting means.

6. A temperature control apparatus comprising a casing having an inlet chamber and a pair of outlet chambers, a partition separating said chambers and provided with separate openings from said inlet chamber to each of said outlet chambers, a valve movable between open and closed positions relative to one of said openings, a thermostatic operator for said valve, an auxiliary valve likewise movable relative to the other said opening, a single adjusting means carried by said casing and adapted for both rotary and axial movement relative thereto, connecting means between said adjusting means and said thermostatic valve for opening said thermostatic valve upon rotary movement of said adjusting means, and connecting means between said adjusting means and said auxiliary valve for opening said auxiliary valve upon axial movement of said adjusting means.

7. A control apparatus comprising a casing having a fuel chamber provided with a pair of valve seats, a valve cooperable with one of said seats for controlling flow of fuel from said chamber, means for operating said valve in one direction relative to said one seat, a second valve cooperable with the other said seat for controlling flow of fuel from said chamber, means for biasing said second valve in one direction relative to said other seat, manually operable means for operating said valves in the opposite direction relative to said seats, means responsive to said operation of said manually operable means and being thereby rendered cooperable with said second valve for holding said second valve in its operated position, and means responsive to operation of said first valve in said one direction for rendering the last said means inoperative and releasing said second valve for operation under its bias in said one direction.

8. A control apparatus comprising a casing having a fuel chamber provided with a pair of valve seats, a valve cooperable with one of said seats for controlling flow of fuel from said chamber, means for operating said valve in one direction relative to said one seat, a second valve cooperable with the other said seat for controlling flow of fuel from said chamber, means for bias-

ing said second valve in one direction relative to said other seat, manually operable means for operating said valves in the opposite direction relative to said seats, said means including a lever engageable with said second valve and being movable to an operative position upon said operation of said manually operable means, a second lever having latching means thereon engageable with the other said lever in said operative position thereof for holding said second valve in operated position, and means carried by the first said valve for tripping said latching means by engagement with said second lever upon operation of said first valve in said one direction and releasing said second valve for operation under its bias in said one direction.

9. A temperature control apparatus comprising a casing having a chamber provided with a pair of spaced valve seats, connections on said casing for conveying fuel to and from said chamber, a valve cooperable with one of said seats for controlling flow of fuel from said chamber, an expansible element in said chamber for operating said valve toward said one seat, means positioned externally of said casing and responsive to temperature changes for causing operation of said element, manually operable means for positioning said valve away from its seat for operation by said element, an auxiliary valve cooperable with the other said seat for controlling flow of fuel from said chamber, means for biasing said auxiliary valve toward its seat, manually operable means for operating said auxiliary valve against said bias to a position away from its seat, said means including a lever engageable with said auxiliary valve and being movable to an operative position upon said operation of said manually operable means, a second lever having latching means thereon and being movable into latching position for engagement with the other said lever in said operative position thereof for holding said auxiliary valve away from its seat, means for biasing said second lever into said latching position, and means projecting from said first valve for operative engagement with said second lever when said first valve is operated toward its seat, said last means being thereby adapted for overcoming said bias for said second lever and tripping said latching means to cause snap-action operation of said auxiliary valve toward its seat.
